Primary Examiner—Alan P. Douglas*Assistant Examiner*—Caron D. Veynar
Attorney, Agent, or Firm—Morton J. Rosenberg; David I. Klein[57] **CLAIM**

The ornamental design for a handle of pots and pans, as shown and described.

DESCRIPTION

FIG. 1 is a front-right-top perspective view of a handle of pots and pans, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of my new design, the broken line showing of a pan is for illustrative purposes only and forms no part of the claimed design.
